PATTERN CONTROLLED DRIVE MECHANISM
FOR MACHINES FOR OPERATING UPON
WARPS

Russell P. Drake, Caledonia, Ill., assignor to Barber-Colman Company, Rockford, Ill., a corporation of Illinois

Application March 20, 1951, Serial No. 216,602

9 Claims. (Cl. 28—44)

1

The invention relates to a drive mechanism for a plurality of members to be operated selectively under the control of a pattern sheet, and has more special reference to a drive mechanism for machines for operating upon warps, such as, for example, as warp drawing machines of the type disclosed in my prior Patent No. 2,400,342, dated May 14, 1946.

The objects of the invention are to provide for the selective operation of a plurality of members such, for example, as the warp rods in a warp drawing machine, by power driven means under the control of a pattern sheet, in a manner such as to insure that the pattern will be relieved of undue pressure by the feeler elements associated therewith; to render the adjustment or timing of the parts less critical; and in general to make the machine more reliable and trouble free in operation.

The objects of the invention thus generally set forth, together with other and ancillary advantages, are obtained by the construction and arrangement shown by way of illustration in the accompanying drawings forming part hereof, in which:

Figure 1 is a fragmentary plan view of a portion of a warp drawing machine of the type shown in said prior patent and having the improved drive mechanism embodied therein.

Fig. 2 is a fragmentary transverse sectional view taken approximately in the plane of line 2—2 of Fig. 1.

Fig. 3 is a fragmentary sectional view taken approximately in the plane of line 3—3 of Fig. 1.

Fig. 4 is a fragmentary sectional view taken in the plane of line 4—4 of Fig. 1 on an enlarged scale.

Fig. 5 is a fragmentary plan view of the mechanism shown in Fig. 4, with certain of the frame parts shown in section.

Referring first to Fig. 1, I have shown my invention applied to a warp drawing machine having two warp rods 10 and 11 to be operated selectively as determined by the pattern sheet P supported by a perforated drum 12. The latter is fast on a shaft 13 mounted upon a rocker 13^a for oscillation toward and from a series of feelers 14 in the form of elongated rods mounted for movement radially of the drum and arranged for actuation selectively in the oscillation of the drum as determined by the pattern P.

The means for driving the drum and imparting oscillating motion thereto is of the character disclosed in said prior patent. In brief, it comprises a drive shaft 15 which, in turn, is con-

nected by bevel gearing 16 with a driven shaft 17 which, in turn, is connected by bevel gearing 18 with a cross cam shaft 18^a parallel with the axis of the drum. Oscillatory motion is imparted to the drum by cam means including a cam 19 on the cross shaft 18^a, acting on the rocker 13^a; and step by step rotational movement is achieved by a bell crank 20 actuated by a cam 21 on the shaft 17, the bell crank having a gearing connection 22 with the drum when the latter is in retracted position (Fig. 2).

Axial movements are imparted to the feeler rods 14 selectively in the oscillation of the drum according to the character of the pattern sheet P, the drum being provided with perforations 26 (Fig. 3) through which the feeler rods may pass except when unperforated areas of the pattern overlie the perforations, in which event the ends of the rods are engaged and the rods advanced to the right in said figure. Return movement of such of the feeler rods which have been advanced is effected by means of a slide 27 connected by side arms 28 with the drum shaft. For this purpose a lost motion connection is provided between the feeler rods and the slide, consisting of a notch 29 in the underside of each rod providing a shoulder 30 engageable by a flange 31 on the slide in the retracting motion of the slide with the drum. It will, of course, be understood that the arrangement is such that when the drum occupies its retracted position the adjacent ends of the feeler rods clear the drum and the pattern thereon to permit of the next stepping movement of the drum by the cam 21.

In accordance with the present invention, the warp rods 10 and 11 are actuated by a drive means deriving power from the main drive mechanism of the machine, through the medium of single revolution clutches 32 and 33 (Fig. 1) controlled by the selectively operated feeler rods 14. In the present instance the continuously driven shaft 17 carries a spiral gear 34 (Fig. 2) driving a similar gear 35 fast on a cross shaft 36. The latter carries a spur gear 37 (Fig. 4) constituting a driver common to the two clutches 32 and 33. As herein shown, the gear 37 meshes with two spur gears 38 and 39 loose on parallel shafts 40 and 41 continuously driven in the operation of the machine.

The clutches 32 and 33 are to all intents and purposes identical so that only one of them need be described. As shown in Figs. 4 and 5, the clutch 32 comprises a driving elements in the form of a disk 42 integral with the gear 38 and having a peripheral notch 43. A second or driven

disk 44 is fast on the shaft 40 and carries a pivoted dog 45 continuously urged by a torsion spring 46 in a direction to press its nose portion 45a toward the disk. The dog is pivoted on a stud 47 supported by the disk and a bracket 47a fixed to the disk. Spur gear trains 48 and 49 (Figs. 1 and 2) respectively connect the shafts 40 and 41 with the warp rods 10 and 11.

The dog 45 constitutes a connecting element between the driving and driven disks 42 and 44. It is normally held disengaged from the driving disk subject to release for entry into the notch 43 thereof under the control of the pattern P. For this purpose the dog has a radial tail portion 50 normally engaged by a stop finger 51 fast upon a rockshaft 52, a similar parallel rockshaft 53 being provided for the clutch 33.

Withdrawal of the stop fingers from the tail portions of the clutch dogs, under the control of the pattern sheet, is accomplished by cam means responsive to the movement of the feeler rods when unperforated areas on the pattern sheet block the rods in the forward movement of the sheet by the drum 12. This cam means comprises in the present instance cam blocks 54 and 55 (Figs. 3 and 4) fixed on the feeler rods 14 and each engageable with a roller follower on an arm 56 fast on the rockshaft 52 or 53, as the case may be. As seen in Fig. 1, each of the rockshafts 52 and 53 is urged by a light torsion spring 57 in a direction to carry the corresponding roller follower arm 56 downwardly into the path of a cam block 54 or 55.

It will be evident from the foregoing that when either of the feeler rods 14 encounters an unperforated area on the pattern sheet and is therefore advanced in the oscillation of the drum, its cam block, engaging with the follower arm 56, rocks the corresponding shaft 52 or 53 against the action of the relatively weak torsion spring 57 so as to withdraw the clutch stop finger 51 out of the path of the dog 45. The dog is thus released for movement by its spring 46 and the nose portion 45a thereof enters the notch 43 in the driving disk 42. The clutch is thus engaged so that rotational movement is imparted to the corresponding warp rod through the spur gear train 48 or 49.

The timing of the oscillating motion of the pattern drum is such that immediately upon the actuation of the feeler rod to trip its clutch, the rod is returned by the slide 27 engaging the shoulder 30 of the rod. Accordingly, before the driven clutch disk 44 completes one revolution, the stop finger 51 is restored to its blocking position with respect to the dog 45 so as to disengage the clutch and thus interrupt the rotation of the corresponding warp rod 10 or 11. To insure against any retrograde movement of the driven clutch disks 44 when thus stopped by the withdrawal of the dog 45, a spring detent 58 enters a peripheral notch 59 in the disk, as seen clearly in Fig. 4.

Experience has shown that the selective operation of the warp rods 10 and 11 from the main drive mechanism of the machine through the medium of single revolution clutches under the control of the pattern sheet renders critical adjustment unnecessary and insures a substantially trouble free operation of this mechanism. More particularly, it has been found that any danger that the feeler rods may be obstructed due to imperfect timing and therefore result in the perforation of unwanted holes in the pattern sheet, is effectually avoided. Thus a substantial saving

is effected through the elimination of periodic shutdowns for repairs.

I claim as my invention:

1. In a machine for operating upon warps having a plurality of parts to be operated, a pattern controlled mechanism for actuating said parts selectively comprising, in combination, a perforated drum for supporting a pattern sheet, a plurality of feeler elements, means for reciprocating the drum, said drum when moving in one direction serving to actuate the feeler elements selectively as determined by the pattern sheet thereon, drive means for each of said parts comprising a clutch having a continuously rotating drive member, a driven member connected with the part to be operated and having a connecting element thereon biased into engagement with the driving member and a stop member normally operative in the rotation of the driven member to disengage the connecting element from the driving member, and means controlled by said feeler elements for actuating the stop member selectively to render their respective connecting elements effective.
2. In a machine for operating upon warps having a plurality of parts to be operated, a pattern controlled mechanism for actuating said parts selectively comprising, in combination, a perforated drum for supporting a pattern sheet, a plurality of feeler elements, means for reciprocating the drum, said drum when moving in one direction serving to actuate the feeler elements selectively as determined by the pattern sheet thereon, drive means for each of said parts comprising a clutch having a continuously rotating drive member, a driven member connected with the part to be operated and having a connecting element thereon biased into engagement with the driving member, and a stop member normally operative in the rotation of the driven member to disengage the connecting element from the driving member, and means responsive to the movements of said feeler elements to render said connecting elements effective selectively, the last mentioned means including actuating devices for the stop members retractile in the return movement of the drum to effect restoration of the actuated stop members to their normal positions.
3. In a machine for operating upon warps having a plurality of parts to be operated, a pattern controlled mechanism for actuating said parts selectively comprising, in combination, a perforated drum for supporting a pattern sheet, a plurality of feeler rods, means for reciprocating the drum, said drum when moving in one direction serving to actuate the feeler rods selectively as determined by the pattern sheet thereon, drive means for each of said parts comprising a clutch having a continuously rotating drive member, a driven member connected with the part to be operated and having a connecting element thereon biased into engagement with the driving member, and a stop member normally operative in the rotation of the driven member to disengage the connecting element from the driven member, and means including cams on each of the feeler rods for actuating the stop members and render their respective connecting elements effective selectively.
4. In a machine for operating upon warps having a plurality of parts to be operated, a pattern controlled mechanism for actuating said parts selectively comprising a perforated drum for supporting a pattern sheet, means for reciprocating the drum, a plurality of feeler rods arranged for

movement with the drum selectively as determined by the pattern sheet, drive means for each of said parts comprising a clutch having a continuously rotating drive member, a driven member connected with the part to be operated and having a connecting element thereon biased into engagement with the drive member and a stop member normally tending to move into the path of the connecting element in the rotation thereof with the driven member and operative to disengage the connecting element from the drive member, and means operative in the movement of the feeler rods to actuate the stop members so as to render their respective connecting elements effective selectively, the last mentioned means including a cam device on each feeler rod and a cam follower operatively associated with one of said stop members, each of said feeler rods having a lost motion connection with the drum operative in the return movement of the latter to shift its cam device relative to its associated follower whereby to permit movement of the latter in a direction to carry the corresponding stop member into clutch disengaging position.

5. In a warp drawing machine having a warp rod, a perforated pattern supporting drum, power driven means for rotating said drum with a step by step movement and for reciprocating the same in timed relation to its stepping movements, a feeler element movable with the drum as an incident to its reciprocation and as determined by a pattern sheet thereon, and means responsive to such movement of the feeler rod for effecting a driving connection between said warp rod and said power driven means comprising a single revolution clutch having a driven member connected with the warp rod, a drive member connected with said power means, a connecting element for said members mounted on the driven member and biased into connecting relation to the driving member, a control device yieldably held in a position to hold the connecting element disengaged from the driving member, and means actuated in the movement of the feeler element with the drum to shift said control device out of holding relation to the connecting element.

6. In a machine for operating upon warps, the combination of a plurality of parts to be actuated selectively, a plurality of pattern controlled selectively operable feeler elements, and drive means for each of said parts comprising a normally disengaged single revolution clutch having a continuously rotating drive member, a driven member, a connecting element pivotally mounted on the driven member and biased for movement into engagement with the driving member, and

a control device operatively connected with one of the feeler elements, said control device normally holding said connecting element ineffective and arranged for movement by its feeler element into position to render the connecting element effective.

7. In a machine for operating upon warps, the combination of a plurality of members to be actuated selectively, a plurality of pattern controlled selectively operable feeler elements, drive means for each of said members comprising a normally disengaged single revolution clutch, and means controlled by said feeler elements for engaging the clutches selectively.

8. In a machine for operating upon warps having a plurality of parts to be operated selectively, a drive means for each of said parts comprising a clutch having a continuously rotating drive member, a driven member connected with the part to be operated and a connecting device, stop means normally operative to render said connecting device ineffective, and pattern controlled mechanism for rendering said connecting device effective selectively including a member operatively connected with the drive means for reciprocation thereby in successive cycles, means operative in the movement of said member in one direction to actuate the stop means selectively, and means operative in the movement of said member in the opposite direction to restore the stop means to normal position.

9. In a machine for operating upon warps having a plurality of parts to be operated selectively in successive operating cycles, drive means for each of said parts including a clutch and a control device therefor having a normal position in which it is effective to maintain the clutch disengaged, and pattern controlled mechanism operative in each cycle of the machine to shift said clutch control devices out of their normal positions selectively whereby to effect engagement of the corresponding clutches and further including means operative at a predetermined point in the cycle following selective disengagement of the clutches to restore the actuated control devices to their normal positions.
